UNITED STATES PATENT OFFICE

147,085

DESIGN FOR A BUILDING

Charles T. Rice, Roswell, N. Mex.

Application January 3, 1946, Serial No. 125,255

Term of patent 14 years

(Cl. D13—1)

To all whom it may concern:

Be it known that I, Charles T. Rice, a citizen of the United States, residing at Roswell, in the county of Chaves and State of New Mexico, have invented a new, original, and ornamental Design for a Building, of which the following is a specification, reference being had to the accompanying drawing, forming part thereof.

Figure 1 is a view in elevation of a building embodying my new design, the opposite side being substantially the same; and

I claim:

The ornamental design for a building, substantially as shown and described.

CHARLES T. RICE.
